UNITED STATES PATENT OFFICE.

ALBERT JOSIAH RICE, OF BUFFALO, NEW YORK, ASSIGNOR TO RICE & ADAMS, A COPARTNERSHIP CONSISTING OF ALBERT J. RICE AND CHARLES S. ADAMS, OF BUFFALO, NEW YORK.

BOTTLE-WASHING MACHINE.

1,216,496.

Specification of Letters Patent. Patented Feb. 20, 1917.

Application filed November 9, 1907, Serial No. 401,453. Renewed October 7, 1916. Serial No. 124,429.

To all whom it may concern:

Be it known that I, ALBERT J. RICE, a citizen of the United States, residing at Buffalo, in the county of Erie and State of New York, have invented certain new and useful Improvements in Bottle-Washing Machines; and I do hereby declare the following to be a full, clear, and exact description of the invention, such as will enable others skilled in the art to which it appertains to make and use the same.

The invention relates to apparatus for cleaning and sterilizing bottles and the like, and belongs, generally, to the class of apparatus described in Letters Patent No. 764,222, dated July 5, 1904, employing the method described in Letters Patent No. 745,752, dated December 1, 1903, granted to Charles S. Adams and myself. The object of the invention is to provide an improved form of apparatus for the purpose mentioned, involving means whereby bottles of different sizes may be washed in one machine through the coöperation of multiple series of jet pipes arranged in sets, the jet orifices of each series being spaced to forcibly project streams of water into the mouths of bottles, which are held in appropriate cases or crates, automatically and intermittently moved longitudinally of the machine above. The invention also contemplates the provision of an improved form of bottle carrying case or crate involving means for supporting and separating the bottles and jet nozzles or pipes which pass freely into the bottles, the rims of the bottle mouths being lifted sufficiently above the supports of the jet nozzles to permit the washing fluid to escape freely. These and other features of the invention will appear more particularly in the accompanying drawings, and in the annexed specification.

In the drawings

Figure 1 is a side elevation of the washing apparatus, the cover being shown in section;

Fig. 2 is a plan view of the apparatus with the cover removed;

Fig. 3 is a fragmentary view, showing

one set of jet pipes in coöoperative relation with the bottle-carrying crate for washing a relatively small size of bottle;

Fig. 4 is a similar view of the apparatus for washing larger sizes of bottles;

Fig. 5 is a plan view of the bottle-carrying crate;

Fig. 6 is an end view thereof;

Fig. 7 is a transverse vertical cross section.

In the drawings 1 indicates a trough or tank which, like the apparatus shown in Patents, Nos. 745,752 and 764,222, hereinbefore referred to, is divided by cross partitions into separate compartments. The number of said separate compartments is to be determined by the character of the washing operation, and the invention contemplates the provision of an appropriate number of compartments to accomplish the purpose desired in the best possible manner. In the form of the invention illustrated in the drawings said trough 1 is divided into two compartments, 2 and 3 respectively, by cross partition 4, which partition is provided with an orifice 5 near the top to establish communication between the two compartments. Above the trough 1 there is disposed a horizontal trackway consisting of parallel angle-irons 6, which may, if desired, be provided with rollers interspersed at appropriate distances to provide bearing for the boxes or crates containing the bottles, as said boxes or crates are moved longitudinally along the trackway. The trough may be conveniently covered by a hood or envelop 70, to prevent the washing fluid being thrown outside of the apparatus during the intervals of moving the boxes or crates to position over the jet pipes.

A pipe 7 leading from the boiler or other source of hot water supply has two branches 8 and 10 which enter tanks 3 and 2 respectively, to supply the washing fluid to said tanks, and said branches 8 and 10 are controlled by valves 9 and 11 respectively. The steam coil 12 is located in tank 3 for the purpose of maintaining the water or washing fluid therein at the desired temperature.

Located at one side of the trough 1 are two rotary pumps 14 and 14', mounted on shaft 30 and driven by pulleys 31, and having suction pipes connected with the respective tanks 2 and 3, and having discharge pipes 13 and 13' connected respectively with manifolds or multiple sets of jet pipes. The apparatus as thus far described is substantially the same as that shown in the patents hereinbefore referred to.

Both of the manifolds or multiple sets of jet pipes are of substantially the same construction and a particular reference to one will serve for a description of both.

After the discharge pipe 13' from pump 14' enters the tank, it is divided into two legs or branches 15' and 18', which are separately controlled by cocks or valves 19' and 20'. Projecting at right angles from branch 15' and parallel with the bottom of the tank are a series of three pipes 16', provided with jet orifices 21, said pipes 16' and orifices 21 being arranged to coöperate with three rows of four bottles each. From pipe 18' extend two pipes 17', provided with jet orifices 21, arranged to coöperate with two rows of three bottles each. The pipes 16' and 17' are, as shown, conveniently arranged in parallel relation just below the trackway 6. The particular number and arrangement of the jet pipes will, of course, depend upon the size of the apparatus and the size and number of the bottles to be washed and the specific arrangements just referred to are mere typical examples, it being understood that the apparatus may be constructed to operate upon any number of bottles in any desired arrangement in suitable carrying cases or crates.

Duplicate sets of jet pipes are arranged in the respective compartments or tanks 2 and 3 and are so disposed therein that the bottles carried in the crates will come into exact registry with the proper jet orifices in said pipes as the said crates are intermittently advanced through the machine in regular order.

Special means are provided for advancing the crates in series along the trackway 6, and for stopping the advance of the series of crates at proper intervals along said trackway and for an appropriate length of time to effect the washing operation. Said means consists of slides 40 mounted in slots in the vertical flanges of the track section 6, at the forward end of the machine, which slides are connected by a cross bar 41, said slides and cross bar constituting a follower which engages the lower edge of the foremost box and forces the same, together with all of the boxes ahead of it, along the trackway a distance equal to the length of a single box. Intermittent reciprocating motion is imparted to the slides 40 by means of the con-

necting rods 39, which are operated by 65 cranks 38 on shaft 36, which is journaled in brackets 37, secured to the end of the machine. Intermittent rotary motion is imparted to shaft 36 by means of mutilated pinions 35, secured to the respective ends of 70 said shaft, which pinions are adapted to be engaged by the teeth of a mutilated gear 34, which latter has one-half of its periphery smooth, to coöperate with a concave surface on pinion 35 to prevent the latter being 75 turned accidentally when the teeth of the gear and pinion are out of mesh, the smooth portions of the respective gears constituting a stop for the movement which effects reciprocation of the slides 40. Motion is imparted to gear 34 by a worm gearing 32 and 80 33, which is operated from shaft 30', driven by pulley 30' which takes its power from a suitable drive shaft.

The boxes or crates in which the bottles 85 are contained, and which constitute an important element of my invention are designed with special reference to general sanitary conditions and facility and economy of operation. Each of said crates conveniently 90 consists of an open framework, preferably made of galvanized metal, which may be readily cleansed and sterilized, and which maintains its proper shape with very little wear under the most severe conditions of operation. Said crate 50 consists of longitudinal top members 51, formed of angle-irons, transverse top members 52 and correspondingly arranged intermediate members 54 and 53, together with reversely arranged 100 angle-iron bottom pieces 66 and transverse bottom members 62, the several rectangular frames thus formed being connected by stay bolts 55, passed through the corners of the frames with suitable spacing sleeves 56 and 57 to hold the frames at appropriate distances and to form a skeleton box or crate. Secured to the longitudinal bottom members 66 are transverse castings 64 which are conveniently formed with properly spaced nipples 62 to which are connected the upwardly extending jet pipes 63. Between the members of the upper frame extend cross wires 58 and 59 which are spaced to engage the sides of bottles inserted mouth downward in the crate and hold them in position against lateral movement. Arranged between the members of the intermediate frame are a series of cross wires 60 and 61 which are spaced so as to surround the necks 115 of the bottles and support the bottles by their shoulders, so that the bottle mouths extend downward and surround the respective jet pipes 63, without, however, coming in contact with the cross bars 64 or nipples 62 120 thereof.

It will be understood that these crates are to be made of appropriate sizes to coöperate

with the trackway 6 mounted above the trough 1 and that the number of jet pipes 63 and cross wires carried by said crates will depend upon the size and number of the bottles to be carried by said crate.

From the foregoing description it is believed that the operation of the apparatus will be clear, but briefly described said operation, taken in connection with Figs. 1 and 2, is as follows: Assuming that the number of bottles in each crate is 12, arranged in 3 rows of 4 bottles each, valves 19 and 19' are opened and valves 20 and 20' are closed, which enables pumps 14 and 14' to force 15 12 jets of water from each set of pipes 16 and 16'. Assuming that a crate is located directly over the respective sets of pipes 16 and 16' the jets of water leaving the nozzles 21 in said sets of pipes are projected forcibly through the jet pipes 63 in the crates into the bottles after which the water escapes from the inverted mouths of the bottles and runs back into the tanks. It will be assumed of course, that the temperature 20 of the water in the respective tanks is regulated in accordance with the operation of the apparatus, as described in the patents hereinbefore referred to. The shaft 30' operated by pulley 30" is driven continuously and in 25 turn drives mutilated gear 34 continuously. As the latter rotates it will be noted that the smooth portion of its periphery lying contiguous to the smooth portion of gear 35 prevents any movement of the latter, so that 30 the crates are accurately held in their adjusted position on the trackway to admit of the jets being forced directly into the bottles. After said gear 34 is revolved through 35 180°, the teeth on one-half of its periphery 40 come into mesh with the teeth on pinion 35 and cause the latter to drive shaft 36 through substantially one revolution, thereby causing the follower, consisting of slides 40 and tie-rod 41, to be advanced to the end 45 of the trackway 6 during the first half of the revolution of said shaft 36, when a crate is placed in position and then to move said crate, together with all of the crates on the trackway ahead of it, forward along said 50 trackway during the other half of the revolution of said shaft, until the smooth portions of the gear 34 and pinion 35 again come into mesh, when the advance of the series of crates is stopped, as before.

55 Should it be desired to operate upon larger bottles in the same machine, say for example, upon six bottles contained in 2 rows of 3 bottles each in a crate, the supply of washing fluid to pipes 15 and 15' is shut off by means of valves 19 and 19', and, correspondingly, valves 20 and 20' are opened to admit of water being forced by the pumps 14 and 14' into the sets of jet pipes 17 and 17', the jet orifices of which are

spaced to register with the jet orifices in the 65 crates containing the two rows of three bottles each.

What I claim is:—

1. An apparatus for cleaning bottles and the like, comprising a trough, pipes in said trough having a series of jet orifices, a trackway over said trough, and a box or crate adapted to hold the bottles in inverted position and to pass along said trackway over the trough, said box or crate having a series of jet nozzles or tubes extending into the bottles and adapted to register with the jet orifices in said pipes. 70

2. An apparatus for cleaning bottles and the like, comprising a trough, pipes in said trough having a series of jet orifices, a trackway over said trough, a box or crate adapted to hold the bottles in inverted position and to pass along said trackway over the trough, said box or crate having a series of jet nozzles or tubes extending into the bottles and adapted to register with the jet orifices in said pipes, and means for intermittently moving said boxes or crates along said trackway. 85

3. A crate for bottle washing machines, comprising a frame, cross bars to separate and support the bottles, and jet nozzles within the frame positioned to project into the bottles supported on said cross-bars. 90

4. A crate for bottle washing machines, comprising a frame, cross bars to separate and support the bottles, and jet nozzles carried by cross bars, below the bottles, said nozzles loosely entering the bottles to permit 100 the washing fluid to escape freely.

5. A crate for bottle washing machines, comprising a skeleton frame, cross bars to separate and support the bottles, cross bars in the lower portion of said frame at a distance to clear the bottle mouths, and jet nozzles carried by said lower bars to enter the bottle mouths. 105

6. In bottle washing apparatus, a stationary series of jet-nozzles and a bottle-carrier having a series of secondary jet-nozzles or tubes adapted to support and project into bottles placed thereon in inverted position. 110

7. In bottle washing apparatus, a stationary series of jet-nozzles, a plurality of bottle carriers each having a series of secondary jet-nozzles or tubes adapted to support and project into bottles placed thereon in inverted position, and mechanism for intermittently advancing the carriers to bring them successively into position with their secondary jet-nozzles or tubes above the stationary jet-nozzles. 115

8. In bottle washing apparatus, a plurality of stationary series of jet-nozzles, a bottle carrier having a series of secondary jet-nozzles or tubes adapted to support and 120

4
project into bottles placed thereon in inverted position, and mechanism for intermittently advancing the carrier to bring it into successive positions with its secondary nozzles or tubes above the several series of stationary jet-nozzles.

In testimony whereof I affix my signature,
in presence of two witnesses.

ALBERT JOSIAH RICE.
